ATTORNEY

UNITED STATES PATENT OFFICE.

CLARENCE S. ANDERSON, OF LAKE GENEVA, WISCONSIN.

RADIATOR.

1,327,797.

Specification of Letters Patent.

Patented Jan. 13, 1920.

Application filed May 9, 1918. Serial No. 233,521.

To all whom it may concern:

Be it known that I, CLARENCE S. ANDERSON, a citizen of the United States, residing at Lake Geneva, in the county of Walworth 5 and State of Wisconsin, have invented certain new and useful Improvements in Radiators, of which the following is a specification.

This invention has relation to radiators 10 for motor vehicles, and the nature and objects thereof will be readily apparent to those skilled in the art to which it appertains in the light of the following explanation of the accompanying drawings, illustrating what I now believe to be the preferred embodiment, or mechanical expression, of my invention from among other forms and arrangements thereof within the spirit of the invention or the scope of the 15 appended claim.

An object of the invention is to provide an improved radiator of the tubular type embodying tubes of a novel construction designed to insure the rapid cooling of the 20 water or other fluid during its passage through the radiator.

Another object of the invention is to provide an improved radiator for motor vehicles of the tubular type in which the tubes 25 are provided with a plurality of external projections or ribs designed to facilitate the conduction of heat from the radiator tubes.

A still further object of the invention is to provide an improved radiator for motor 30 vehicles of the tubular type in which the tubes are formed in a novel manner with a view to permitting easy repair in the event of injury to the radiator and at same time to permit the radiator tubes to be initially 35 constructed at a greatly reduced cost.

A still further object of the invention is to provide a radiator tube of a novel construction for radiators of motor vehicles designed to permit the expansion to some extent of water in the event that the water 40 congeals during periods of low temperature so as to prevent the disruption of the tubes and consequently prevent the leakage of the radiator at any point.

In addition to the foregoing my invention 45 comprehends improvements in the details of construction and arrangement of the correlative parts to be hereinafter more fully described and particularly set forth in the 50 appended claim.

In the accompanying drawings in which similar and corresponding parts are designated by the same characters of references throughout the several views in which they appear:—

Figure 1, is a fragmentary view in front elevation of a portion of a radiator embodying my improved radiator tube.

Fig. 2, is a view, partly in side elevation and partly in section of one of the tubes. 65

Fig. 3, is a view in vertical section taken on the line 3—3 of Fig. 2, and

Fig. 4, is a horizontal section.

Fig. 5 is a detail perspective view of a portion of one of the side closures of the 70 tubes.

With reference to Fig. 1 of the drawings, 75 10 indicates a plurality of radiator tubes, preferably disposed in parallelism and in vertical position to connect the upper chamber or header 11 of the radiator with the lower chamber (not shown). Since the construction of tubular radiators is well known a further exposition of the principles embodied therein is not thought necessary 80 in this application. Suffice to say that my improvement consists of a new construction of a radiator tube, the same being shown in detail in Figs. 2, 3 and 4. Each radiator tube is formed of a pair of metallic strips 85

11 and 12. These strips are bent at uniformly spaced points throughout their length to form outwardly extending portions 13, defining ribs upon the outer surface of the tube and pockets 14 communicating with the 90 interior of the tube. The ribs 13 are formed in such a manner as to present a slightly inclined surface relative to the horizontal, the ribs at one side of the tube being inclined oppositely to those at the other side. 95

The vertical portions of the strips are disposed in spaced relation by means of vertical strips 15 at the forward and rear edges of the tubes said strips 15 being bent double as shown and their rounded edges directed outwardly. The joint between the strips 15 and the strips 11 and 12 may be closed by means of soldering in the usual manner. As shown in Fig. 5 the strips 15 may be cut away at points to form oppositely extending 105 fingers 16, located at proper points to form closures for the ends of the pockets 14, a tight joint being effected by means of soldering. It will be obvious, however, that the ends of the pockets may be closed by 110

means of end plates which may be formed separately from the strips 15 if desired.

It will be obvious in use, that during the passage of the water downward through the 5 tubes the water may flow in and out of the pockets 14, and from a pocket at one side of the tube to a pocket on the other side, the pockets having an effect to slightly retard the flow of water to insure its cooling

10 before entrance into the water jacket of the engine. The provision of the ribs 13 defining the pockets also provides an increased surface for each tube so as to facilitate the conduction of the heat away from the tube.

15 It will be obvious that owing to the inclination of the ribs 13 during forward motion of the vehicle the air is deflected toward opposite sides of the tubes, thereby insuring the rapid conduction of heat away from the 20 tubes. These tubes, being of more or less expansible construction will expand somewhat in the event that the water should freeze during periods of cold weather the pockets expanding slightly, the sides 11 and 25 12 of the pockets also separating slightly to permit expansion of the congealing water thereby preventing damage to the tubes themselves. It will be obvious that since the joints of the tubes are located at the front 30 and rear of the radiator, access to the joints for resoldering may be readily obtained. Other uses and advantages will readily occur to those skilled in the art to which this invention appertains.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the appended claim.

Having thus described my invention what I claim as new and desire to secure by Letters Patent is:—

A radiator tube, comprising closely related companion strips, each strip having portions at regular intervals bent outwardly to form hollow ribs which project laterally 50 at a right angle and which incline in the direction of the width of the strip and tube, the ribs on one side of the tube inclining in an opposite direction to the ribs on the other side of the tube, and closing strips 55 secured between and connecting the edges of the tube strips, each closing strip being doubled upon itself and having parts of the folded portions cut and bent laterally in opposite directions to close the ends of the 60 hollow ribs.

In testimony whereof I affix my signature in presence of two witnesses.

CLARENCE S. ANDERSON.
